HAIRPIN

Sebastian J. Franco and Hazel Bergren,
Omaha, Nebr.

Application November 18, 1938, Serial No. 241,198

3 Claims. (Cl. 132—50)

This invention relates to the hair dressing art and more particularly to hairpins.

It is an object of the invention to provide a hairpin for professional hair dressers' use to be placed in the hair temporarily while curling or waving the hair and of a character so constructed that the pin is easy to position accurately in the hair and will be effectively held within the hair for holding curls and the like in place, said construction being such that a plurality of the pins may be rapidly withdrawn from the hair by the use of an electro-magnet after a hair processing operation.

A further object of the invention is to provide a hairpin for the above stated purposes having a plurality of tines so joined together that fine hairs will not bind between the tines when the latter are placed in the hair.

Another object of the invention is to provide a hairpin having a plurality of straight shank tines formed of resilient material adapted to be closely compacted by an operator for accurate insertion into the hair and so arranged that the free ends of the tines will spread away from each other after being compacted from a normal position for temporarily gripping the hair in a manner whereby the straight shank tines are easily and quickly removed from the hair by a magnetic means.

Other and further objects and advantages of the invention will be understood from the following detailed description thereof, reference being had to the accompanying drawing in which:

Figure 1 is a side elevation of the new device. Figure 2 is a view similar to Figure 1, the device being illustrated turned at an angle of 90 degrees with respect to the showing thereof in Figure 1.

Figure 3 is an end view of the tines of the device.

Figure 4 is a diagrammatic illustration of a mode of compacting the tines of the device prior to application to the hair.

Figure 5 is an end view of the tines of a modified form of the device.

Figure 6 is a side elevation of the said modification, the device being turned about 30 degrees with respect to the showing thereof in Figure 5.

Referring now to the drawing for a more particular description 10 and 11 indicate oppositely disposed tines of the new device formed of a soft iron wire, the latter having a portion 12 bent upon itself for providing tines susceptible to magnetic attraction.

The new device further includes tines 13 and 14 formed of the said material and in the same manner having a joining bent portion 15.

The portion 15 is placed upon the portion 12, as shown in Figure 1, in a manner whereby they are of semi-cruciform in plan, as shown in Figure 3, and joined together as at 16 by any suitable means such as solder, spot welding or, if desired, the portions 12 and 15 may be twisted about each other for joining the tines together 10 at the point 16 and in a manner whereby the outer ends of the tines are normally disposed divergently with respect to their common center or the point 16 and of cruciform arrangement in plan with respect to oppositely disposed ends. 15

Referring to the modifications shown in Figures 5 and 6, said modifications include tines 10' and 11' having a common joining portion 12' together with tines 13' and 14' having a similar joining portion 15'. The portions 12' 20 and 15' are joined together by any suitable means in a manner whereby the tines are normally disposed outwardly and divergently with respect to their common center, the extreme outer ends of the tines defining a substantially rectangular 25 outline in plan, as shown in Figure 5, and the tine 13' being arranged approximately opposite with respect to the tine 11', the tine 10' being arranged approximately opposite with respect to the tine 14' whereby the ends of the tines 10' 30 and 14' are arranged in approximate cruciform with respect to the ends of the tines 11' and 13' as shown in Figure 5.

In operation and in order to insert the new device in the hair the outer ends of the tines 35 are compacted towards each other, the operator grasping the device adjacent to the portion 15 and compressing the tines together between his thumb and forefinger, as shown in Figure 4, whereupon the device may be inserted rapidly 40 into the hair and upon the operator releasing his fingers the tines spread apart to approximately their normal position, as shown in Figure 3, for gripping the hair and holding it in place while the hair is being processed. 45

As thus described it will be understood that after placing a large number of the devices in a head of hair and after said processing, the pins may be rapidly withdrawn by passing a magnet over the hair since the tines are of straight 50 shank construction and this operation may be consummated without disturbing the treated hair and without marring the effect of the ornamental treatment thereof.

From the foregoing description it is thought 55

to be obvious that a hairpin constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish it to be understood as limiting ourselves to the precise arrangement and formation of the several parts herein shown in carrying out our invention in practice except as claimed.

We claim:

1. A hairpin constructed of two wires comprising four tines having straight shanks and of approximately equal length, said tines being formed of resilient material the latter being such that it is susceptible to the influence of magnetic attraction, ends of the tines common to one wire being arranged in cruciform with respect to the two ends of the tines common to the other wire, said tines being disposed convergently from

said ends towards their other ends, said other ends being joined together.

2. A hairpin constructed of two U-shaped wires formed of resilient material comprising four tines each having a straight shank portion, said wires being joined together at the closed ends thereof, said shank portions each extending outwardly and divergently from said closed ends in a different direction.

3. A hairpin adapted for temporary use while performing a hair processing operation comprising two resilient wires both having two tines provided with straight shanks throughout their entire length, whereby the tines may be compressed toward each other and into a common plane throughout substantially their entire length to permit facile insertion of the tines into a mat of hair, said wires being joined together with their tines angularly disposed to one another.
